UNITED STATES PATENT OFFICE.

JOHN A. KOTTLER, OF MILWAUKEE, WISCONSIN.

MAT.

1,316,902.

Specification of Letters Patent. Patented Sept. 23, 1919.

Application filed October 18, 1917. Serial No. 197,266.

To all whom it may concern:

Be it known that I, JOHN A. KOTTLER, a citizen of the United States, and resident of Milwaukee, in the county of Milwaukee and 5 State of Wisconsin, have invented new and useful Improvements in Mats, of which the following is a description, reference being had to the accompanying drawings, which are a part of this specification.

10 My invention has relation to improvements in mats, more especially adapted for use in connection with the running-board of a vehicle, such, for instance, as an automobile.

15 The primary object of the invention is to provide a construction wherein the holding member of the clip which secures the mat removably to the running-board can be readily adjusted and detachably secured to a

20 completed mat, without the necessity of permanently embedding into (to any extent), or interweaving with, the mat, of the holding member of the clip.

A further object contemplated is the provision of means whereby the holding member of the clip is capable of being pivotally turned, so as to be caused to lie flat against the under surface of the mat.

With the above, and other incidental, objects in view, the invention consists of the devices and parts or the equivalents thereof as hereinafter more fully set forth.

In the accompanying drawing:

Figure 1 is an inverted plan view of the 35 mat embodying my improvements, showing the holding clips turned within their pivotal connections so as to lie flat against the under surface of the mat;

Fig. 2 is a transverse section of the mat 40 on the plane indicated by the dotted line 2-2 of Fig. 1, and showing the holding clips turned to the positions they occupy when in use; and

Fig. 3 is a vertical section on the line 3-3 45 of Fig. 2.

In carrying out my invention, I provide the mat 4 with one or more, and preferably two, securing clips. Each clip consists of a single upper straight member 5 having its 50 end bent at an angle as indicated at 6, to form a short angular extension, and a lower single under member 7, spaced a desired distance from the upper member, said under member being curved around from the upper member in an opposite direction than 55 is the short angular extension bent, and

thence upwardly, with its terminal portion curved and bent downwardly as clearly shown in the drawing.

The upper member 5 of each clip is forced 60 through one or more of the longitudinal strands of the mat, as shown at 8, on the under side of said mat, and the bent end 6 of said upper member is forced up into the mat, as most clearly shown in Fig. 2 of the 65 drawings, the bent end thereby acting as a stop to prevent the clip from accidentally working out from engagement with the mat.

As a further means for holding the upper 70 arm of the clip, I employ loops 9, preferably formed of small wire, each loop comprising a plurality of strands of wire having their ends twisted together and the said twisted ends secured in the mat, as most clearly 75 shown in Fig. 2.

It is one of the objects of the invention to have the upper member 5 fit within the loops 9 with at least sufficient looseness to permit the holding clip to be turned on the axis of the upper member to the position shown in 80 Fig. 1, when the clips are not in use, and to be turned to the opposite position, shown in Fig. 2, when it is desired to use the clips, or in other words, to attach the mat to the running-board.

In the adjustment of each clip to the mat, the upper member of said clip is forced 85 through the longitudinal strand on the under side of the mat, as indicated at 8, the bent end 6 at this time being held so that 90 it will be on a plane with the surface of the mat. When the clip has been forced inwardly a sufficient distance, the said clip is then turned so that the bent end 6 will be forced up into the material of the mat, as 95 clearly shown in Fig. 2.

The next step is to secure the loops 9 around the upper member 5 of the clip. When it is desired to adjust the mat to the upper surface of the running-board of a vehicle, as, for instance, the running-board of an automobile, all that is necessary to be done is to force the lower members 7 of the clips beneath the running-board, the mat and the upper members of the clips of course 100 resting upon the upper surface of the running-board. In this manner, the mat is reasonably secured to the running-board.

When it is not desired to use the mat, it can be readily withdrawn from engagement 110 with said running-board.

From the foregoing description of my in-

vention, it will be seen that I provide a construction wherein the upper member of the clip can be most readily and expeditiously connected to a mat, and as readily withdrawn therefrom, when necessary, with the result that if a clip should become broken, another clip can be substituted with but little trouble.

It will be further seen that I provide a construction wherein the clips can be turned flat against the under surface of the mat. This is very convenient, inasmuch as the clips can be placed flatwise against each other, and thereby much space is saved. Furthermore, by turning the clips flat against the surface of the mat, there is much less danger of breaking the clips by said clips being struck by a person's foot, or by some other object, when the mat is not in use. When the mat is not in use it is frequently carried on the floor of the machine, and there is always danger in such cases of the foot or other object striking the clips and breaking or damaging the same.

The clips are preferably, although not necessarily, of wire, and are also preferably, but not necessarily, resilient or springy in character.

The mat, in connection with which I employ the clips hereinbefore described, is preferably of a peculiar construction which coacts with, or, in other words, has a direct coöperation with the clips. The mat is advisably a special creel woven mat, woven by hand, or by hand loom, and consists of longitudinal strands 10, and transverse strands, said transverse strands, on the under side of the mat, being formed into downwardly projecting loops 11. A plurality of these loops are arranged close together, and constitute a transverse line composed of a plurality usually from 4 to 6, loops. The next line of loops is similarly constituted, but spaced a slight distance from the adjacent lines, and so on throughout the entire under surface of the mat, with the result that there are a series of upwardly extending recesses between every two lines of loops. The longitudinal strands 10 pass through these loops, as most clearly shown in Figs. 1 and 2.

Within one of the upwardly extending re-

cesses between two lines of these loops is disposed the upper member 5 of each clip. By so disposing the member 5 of the clip, said member becomes sunk into the mat to a certain extent, or, in other words, the loops 11 extend downwardly a greater distance than the surface of the arm 5, and consequently the said arm 5 is disposed above the plane of the lower surface of the loop.

The advantage of this arrangement is that in sliding the mat over the top surface of the running-board, when adjusting the mat to the running-board, there are no exposed surfaces of the upper arms 5 to contact with the upper surface of the running-board, and hence there is no marring or scratching of the upper surface of said board, as is the case with other constructions wherein the upper arm of each clip is exposed.

What I claim as my invention is:

The combination with a foot-mat having a series of transverse strands formed into loops, and a series of longitudinal strands passing through said loops, of a holding clip for the mat comprising a straight single upper member mounted on the bottom of and extending transversely of said mat and positioned between the loops of two adjacent rows of said transverse strands and in a plane above the lower edges of said loops, said straight member being supported in position by one of said longitudinal strands, and one end of said straight member being provided with a relatively short right-angle extension which penetrates upwardly into the body of the mat, and said straight member also having formed at its other end a downwardly and backwardly extending member which is curved to clamp the mat to a running board of a vehicle, said backwardly extending member being bent from said straight member directly opposite to the direction of the short right-angle extension, whereby the clip can be turned on the axis of the straight member to fold the clip against the bottom of the mat and at the same time retain the short extension in the mat to prevent the displacement of the clip in a direction of its length in both the open and folded positions of the clip.

In testimony whereof, I affix my signature.

JOHN A. KOTTLER.
